UNITED STATES PATENT OFFICE.

DON L. QUINN, OF OAK PARK, ILLINOIS, ASSIGNOR TO CHICAGO MILL AND LUMBER COMPANY, OF CHICAGO, ILLINOIS, A CORPORATION OF ILLINOIS.

SHIPPING CRATE.

Application filed August 15, 1923. Serial No. 657,474.

To all whom it may concern:

Be it known that I, DON L. QUINN, a citizen of the United States of America, and a resident of Oak Park, county of Cook, 5 and State of Illinois, have invented a new and useful Improvement in Shipping Crates, of which the following is a specification.

This invention relates to shipping crates 10 and particularly crates for fluid containers.

The main objects of this invention are to provide a reusable shipping crate having improved means for fastening the cover portion to the main body portion which will 15 permit the crate to be conveniently opened without destroying any part thereof; to provide a shipping crate which is adapted to support the container in a tilttable position to permit its contents to be readily 20 poured; to provide a crate of this kind wherein the parts thereof are readily adjustable to permit ready tilting of the container; and to provide a crate of the above 25 description which is simple, inexpensive and durable and which is of convenient form for storage or shipping purposes.

An illustrative embodiment of this invention is shown in the accompanying drawings, wherein—

30 Figure 1 is a top plan of a crate to which this invention is applied.

Fig. 2 is a side elevation of the same.

Fig. 3 is a side elevation of the same taken at right angles to Fig. 2.

35 Fig. 4 is a vertical section of the crate showing the pivoted end portion in an extended position.

Fig. 5 is a vertical section of the crate showing the parts arranged for tiltably 40 supporting the container.

The common form of shipping crate is designed with a view to making them so inexpensive that they can be profitably used for one-way shipments and then destroyed.

45 Usually such crates consist of panel sections nailed together and which are broken apart when the crate is opened. The crate herein shown includes improved means for fastening the cover portion of the crate to the

50 main portion so as to permit the crate to be conveniently opened without destroying

any part thereof. This improved construction provides a reusable crate which is practically as inexpensive to manufacture as the crates heretofore used for only one-way 55 shipments.

Shipping crates heretofore in use for fluid containers have been cumbersome to handle and, therefore, to pour out the contents from the container, it has been customary 60 to first remove the container bodily from the crate. In the specific embodiment herein illustrated, the present invention is applied to a crate having relatively adjustable 65 portions arranged to permit the main portion to be readily converted into a carriage tilttable on the other portion to facilitate the pouring of the contents. The particular construction herein illustrated is adapted 70 for use in handling the sheet metal containers commonly used in the shipment of motor oil.

Referring to the drawings, the crate illustrated includes a main body portion 1 having pivotally connected thereto an adjustable closure portion 2 which is shiftable into a position for tiltably supporting the main portion 1 to facilitate the pouring of 75 the contents of a container 3, carried in the crate.

In the construction shown, the main crate portion 1 includes a plurality of frame bars 4 forming the corners of the crate and to which are secured transversely disposed slats 5 constituting the walls and bottom. 85 Formed on the inner faces of the corner bars 4, are grooves 6 forming guideways for a pair of oppositely disposed cleats 7, which are arranged so as to be slidable longitudinally of the crate.

In the form illustrated, the adjustable portion 2 constitutes the cover of the crate and comprises spaced bars 8 connected by slats 9. Formed in the cross bars 8 are mortises 10 and tenons 11 adapted for engagement with tenons 12 and mortises 13, formed in the upper end of the main frame bars 4 for holding the crate portions 1 and 2 in interfitting relation when the cover is closed.

Secured to the outer face of the cross bars 8 of the cover portion 2, are oppositely dis-

posed arms 14 arranged to embrace the main portion 1 of the crate and having their inner ends pivotally connected to the adjustable cleats 7 by rivets 15. The improved arrangement of the arms 14 and cleats 7 provides for the mounting of the end portion 2 on a sliding pivot, which permits the portion 2 to be drawn outwardly to a position where it will clear the corners 10 of the rectangular frame portion 1 before it is swung into open position or into the position for tiltably supporting the crate.

The cover part 2 is locked in its closed position for the purpose of shipping, by 15 suitable means such as a wire band 16 extending around the crate, or by means of a wedge 17 inserted between one or both cleats 7 and the upper edges of the grooves 6, as shown in Figure 2.

20 To use the crate as a carriage for tiltably supporting the container while its contents are poured, the cover portion 2 is first drawn out to the position shown in Figure 4, and is then swung around the main portion 1 25 into the position shown in Figure 5, so as to form a base or standard upon which the main portion 1 is tiltably supported. The main portion of the crate may then be conveniently tilted at any desired angle for 30 pouring out the contents of the container.

Although but one specific embodiment of this invention has been herein shown and described, it will be understood that numerous details of the construction shown may 35 be altered or omitted without departing from the spirit of this invention as defined by the following claims.

I claim:

1. A shipping crate having a pivoted portion 40 normally disposed in substantially the plane of one face of the crate and shiftable from its normal position into a position to tiltably support said crate.

2. A shipping crate having a portion pivotally connected to said crate and arranged to normally form one wall thereof, said wall portion being shiftable from its normal position into a position to tiltably support said crate.

50 3. A shipping crate having a portion pivotally connected thereto and arranged to normally form an end closure for the crate, said end portion being shiftable from its normal position into a position to form a base for tiltably supporting said crate.

4. A shipping crate having a portion pivotally connected thereto and normally disposed in substantially the plane of one wall of the crate, the axis of said pivoted portion 60 being shiftable relative to the main portion of the crate so as to permit said pivoted portion to be shifted around said main portion into a position to tiltably support said main portion of the crate.

5. A shipping crate having a portion piv-

otally connected thereto and arranged to normally form an end closure for the crate, the axis of said pivoted end portion being shiftable relative to the main portion of the crate so as to permit said pivoted portion to be drawn out of its normal plane and shifted around said main portion into a position to form a base for tiltably supporting said main portion.

6. A shipping crate having a portion arranged to normally form an end closure for the main portion of the crate, said crate including a cleat having a limited relative movement with respect to said main portion, said end portion being pivotally connected 70 to said cleat so as to permit said end portion to be drawn out of its normal plane and shifted around said main portion into a position for tiltably supporting said main portion.

7. A shipping crate having a rectangular main portion including a pair of cleats arranged in opposite sides of the crate and shiftable longitudinally of said main portion, and an end closure portion having oppositely disposed arms pivotally connected to said cleats so as to permit said end portion to be drawn out of its normal position and shifted into a position for tiltably supporting said main portion.

8. A shipping crate having a rectangular main portion including a pair of cleats arranged in opposite sides of the crate and shiftable longitudinally of said main portion, and an end portion arranged to normally form a closure for one end of the crate, said main and end portions having parts adapted for interfitting engagement when said end portion is closed, said end portion having oppositely disposed inwardly projecting arms pivotally connected to said cleats to permit said end portion to be drawn outwardly from its normal position and shifted around said main portion into a position to form a base for tiltably supporting said main portion.

9. A shipping crate having a portion pivotally connected thereto and arranged to normally form an end closure for the crate, said end portion being shiftable from its normal position into a position to form a base for tiltably supporting said crate, and means for locking said end closure portion in its normal position.

10. A shipping crate having a portion thereof arranged to normally form a closure for an opening in one side of said crate, said closure portion being pivotally connected to the main portion of the crate, the axis of said pivoted portion being shiftable relative to the crate so as to permit said pivoted portion to be drawn out of its normal position and swung clear of the main portion for opening the crate.

11. A shipping crate having a rectangu-

lar main portion including a pair of cleats arranged in opposite sides of the crate and shiftable longitudinally of said main portion, and an end portion arranged to normally form a closure for one end of the crate, said end portion having parts pivotally connected to said cleats to permit said end portion to be drawn out of its normal position and swung clear of said main portion for opening the crate. 10

Signed at Chicago this 9 day of August 1923.

DON L. QUINN.
